EXPANSIBLE SPINNER MECHANISM

Lydia B. Koch, New York, and Irving F. Mandell,
Rochelle, N. Y.; said Mandell assignor to said
Koch

Application April 3, 1939, Serial No. 265,832

9 Claims. (Cl. 93—36.5)

This invention relates to mechanism for spinning—by which term is meant deformation by pressure applied by rotative instrumentalities—the edges of container body shells of fibrous material, as paper, and more particularly for containers having a frustro-conical shape.

Although the present disclosure provides for curling the smaller end of the container body shell only, to form a reinforced lip, it is sufficiently broad and comprehensive to cover the curling of a container body wall and an included closure skirt, to constitute a tightly seamed joint at either the small or large end of a container.

Heretofore, the curling of frustro-conical containers has been accomplished by a plurality of 10 spinning heads in order to provide for the constantly increasing diameter of the spun portion as the spinning operation advances from the edge of the container.

This condition has always resulted in a variable 20 relation between the curl forming members and the edge undergoing curling, to the detriment of the spinning action.

An object of this invention is to provide an automatically expandible spinning means whereby a single spinning device will operate in such manner as to follow the angle of the taper of the container, thereby maintaining a fixed relation of the curl forming members to the material being curled during the entire movement of the spinning head, thus rendering it possible to obtain a closer curl than has been done by previous methods.

A further feature is in the provision of improved means for controlling the compactness of 35 the curl by the expansion of the curl forming members.

Other aims and objects of a highly advantageous nature will appear as the description 40 proceeds, and are accomplished by the novel and practical construction and combination of parts hereinafter described and illustrated in the accompanying drawings, constituting a material component of this disclosure, and in which—

Figure 1 is a side elevational view of a complete embodiment of the invention, showing a container on its mandrel.

Figure 2 is an end view of the spinner head, looking on line 2—2 of Figure 1, and drawn to an enlarged scale, the container omitted.

Figure 3 is a transverse sectional view taken on line 3—3 of Figure 1, also drawn to an enlarged scale.

Figure 4 is a perspective view of one of the spinner elements in detail.

Figure 5 is a partial side elevational, partial sectional view, showing the operative mechanism.

Figure 6 is a longitudinal sectional view, showing the spinner elements as disposed during the initial stage of operation.

Figure 7 is a similar sectional view showing the same elements in a further advanced position.

Figure 8 is a top plan view of the container mandrel and associated operative parts.

Figure 9 is a longitudinal sectional view of the same with a container shell in position on its mandrel.

Figure 10 is a similar view of the same parts, but showing the shell as ejected.

Figure 11 is a fragmentary longitudinal sectional view of the tapered end of the mandrel, showing an alternative construction.

Referring in detail to the drawings, the numeral 20 designates in general the frame of the machine having fixed on its under side, near its rear end, a bracket 21 carrying a stud 22 on which is journalled a two-armed lever, its shorter arm 23 having at its end a follower roll 24 engaging in the groove of a cam 25 having a single throw of definite shape.

The cam is fixed on a constantly driven shaft 26 by which the lever is actuated, its longer arm 27 extending upwardly through an opening in the frame 20.

Another bracket 30 (see Figure 5), fixed on the upper surface of the frame, is provided with side extensions 31, finished parallel with the frame, to serve as guide rails for a slide 32 having at its rear a raised lug 33.

Pivottally engaging the lug 33 is a fork 34, connected, by a right and left adjusting screw 35, with a similar fork 36, pivoted, as at 37, to the lever arm 27.

A housing 40, fixed on the slide 32, carries spaced anti-friction bearings 41 held by end plates 42 and provided with oil seals 43.

Mounted in the bearings 41 is a sleeve 44 having an enlarged shouldered portion 45 intermediate the bearings; the rear reduced portion of the sleeve has secured to it a pulley 46, held by a nut 47 and driven by a belt 48 at a high rate of speed by any convenient means, as a motor, not shown.

The forward end of the sleeve 44 (see Figure 6), has fixed upon it a spider 50 held by a clamp nut 51, this spider being plurally recessed radially, as later described.

A spindle 55, is keyed at 54 to slide in the sleeve

44 and is journalled at its reduced rear end, in an anti-friction bearing 56, which is held in position thereon by a nut 57, and mounted in a housing 58.

The housing 58 is provided with two opposed radial pins 59 on which are pivoted the ends 60 of a clevis connection made in two equal half sections, for the purpose of assembly, held together as by a bolt 61 and dowels 62; the opposite end of the connection link presents similar forks 63, pivotally engaged by a pin 64 passing through the extreme end of the lever 27, which thus imparts a differential movement to the spindle 55 and slide 32 respectively.

The spindle 55 has at its front end a reduced diametral portion on which is secured a spinner head 70 provided with a plurality of segmental face flanges 71 and ledges 72, the latter having small curved fillets at their junction with the head, and are bevelled inwardly towards the axis 20 at their front surfaces for clearance.

Intermediate the flanges 71 are recesses 74 having at each side lateral lugs 75 in which are fixed pivot pins 76 for movable curl forming members 80, substantially right angular in shape and having in their forwardly extending portions, arcuately curved transverse grooves 81, their edges smoothly rounded, as indicated in Figure 4; these grooves act, upon contact with the container edge, to closely curl the edge inwardly, in co-operation with the flanges 71 and ledges 72 at the initial stage of operation.

The curl forming members 80 have radially extending pairs of lugs 82, in the spaces 83 between which are freely pivoted, on pins 84, the outer ends of links 85, pivotally connected by pins 86 within the recesses 87 of the spider 50.

An anti-friction thrust bearing 90, having a stud 92 set in its inner portion, is set firmly in the outer end of the head 70, within a cup 91, axially with respect to the spindle 55, the purpose of which will later appear.

The lever 27, which by its swinging action and because of the differential radial position of pins 37 and 64, with respect to the pivot point 22, imparts a differential movement to both the spindle 55 and sleeve 44, the spindle moving relatively further than the sleeve as may be seen in Figures 1 and 6. The difference in this motion accomplishes relative movement between the spider 50 and spinning head 70 so that by action of the connections 85, outward movement of curl forming elements 80, is accomplished during the forward motion of the spinning device and reversely during the rearward motion. This outward motion of the curl forming elements follows substantially the angle of the taper of the conical container body.

The support mandrel for the container may be one of a series carried by some form of a turret-like structure, or other device for receiving and discharging the paper body shells, and for holding them firmly when operated upon.

A preferred type of device is indicated in Figures 1, 6, 7 and more comprehensively in Figures 8 to 11 inclusive, which will now be described.

A rear support 100, which may be part of a turret or like mechanism, and a similar front support 101, constitute the foundation of the 70 container mandrel operating device; these supports are rigidly connected, in spaced relation, by a pair of bars 102, dowelled and held by screws thereto at their ends, and by the supporting structure.

5 The forward support 101 has on its front side, either integral or rigidly secured, a container body shell mandrel 103, having a conical forward portion 104 and a recess 105 at its juncture, this mandrel snugly fitting, at all points, within the paper shell X, as indicated in Figure 9.

Both supports 100 and 101 are bored to receive a hollow shaft 110 which extends midway into the mandrel 103; the inreaching portion of the shaft is counter-bored, and set firmly therein in a bushing 111.

Secured in the end of the mandrel is a threaded bushing 112, these bushings providing spaced bearings for a slidable spindle 113, having a reduced threaded terminal 114 at its front end, and on which is secured a circular plunger die 115, which has a special shape including a curved face.

Fixed on the spindle 113, within the reduced bore 117 of the mandrel, is a collar 118 and interposed between the collar and bushing 110, encircling the spindle, is a helically coiled expansion spring 120 adapted to urge the spindle forward, together with the die 115, into its normally outward position.

25 A buffer spring 121 may be interposed between the collar 118 and bushing 112, or, if preferred, the collar 118 may be fitted to act as a dash-pot 119 (see Figure 11) to cushion the action of the spindle 113, preventing undue violence.

Fixed on the inner extending end of the spindle 113 is a latch collar 124 to co-operate with a detent latch 125, pivoted in a recess in the hollow shaft 110, on a pin 126, and urged into operative position by a spring 127, these elements acting to retain the spindle and die 115 in retracted position until the container is ejected, as in Figure 10, as later described.

Slidably mounted on the guide bars 102 is a cross head 130 having a projecting stud 131, flattened at opposite sides of its head to engage a cam actuator, indicated at Z, but which constitutes no part of the present disclosure.

The reduced, through reaching point 132 of the stud, as the cross head moves forwardly, makes contact with the rear, lever-like portion of the detent latch 125, releasing the collar 124, permitting the spindle 113 to advance to its normal outer position after the container is partly removed from the mandrel 103.

The cross head 130 is further provided with a spring pressed detent 133, normally seated in a recess 134 formed in the rear support 100.

Oppositely extending lateral arms 135, on the cross head 130, receive the rear ends of ejector rods 136, which are adjustably secured by nuts 137; the forward portions of the rods are guided in openings in the front support 101, and are secured in an ejector ring 138, slidable on the mandrel 103 to displace a container shell.

In operation, a container is placed upon the mandrel 103, when in a position offset away from axial alignment with the spinning head, at which time the plunger die 115 is in position away from the end of the mandrel and the ejector ring 138 is toward the rear end of the mandrel to clear the oncoming container.

The mandrel assembly is then moved into axial alignment with the spinning head, and the head, with its associated parts, is caused to move slowly forward to meet the edge of the container X by means of the cam 25 and lever 27.

The differential motions of the sleeve 44 and spindle 55, by action of the lever 27, with its differently located pins 37 and 64, cause the spin-

dle 55 to travel a somewhat greater distance than the sleeve 44. This distance is substantially uniform in its increase in relation between the sleeve and spindle during the forward stroke of the spinner assembly. By this differential motion, the links 85, connecting the spider 50 and curl forming elements, cause a substantially uniform expansion of the effective working diameter of the curl forming grooves 81, in a manner to follow a uniform relation to the increasing diameter of the taper wall of the container during spinning action as the head 70 is advanced.

During the first stage of the spinning, from the instant the curl forming grooves 81 contact the edge of the container body wall X until it is advanced somewhat further than indicated in Figure 6, the outer portions and parts of the throat of the curl forming grooves act to start the curling of the container wall inwardly and the segmental flanges 71 and ledges 72 co-act to limitedly curl the container wall inwardly and rearwardly in a relatively close formation.

After the curl forming grooves 81 have been expanded, due to their advancement, so that the inner portion of the grooves 81 have passed outwardly, beyond the range of the ledges 72, the curl, which has then become partly recurled, is fully controlled by the grooves 81 to the end of its advancement, as in Figure 7.

After the spinner head is advanced slightly beyond the point of contact with the container wall, the stud 92 in the free turning thrust bearing 90 strikes the end 114 of the plunger die shaft 113, as shown in Figures 6 and 7. From this point on to the completion of the curling, the spring 120 holds the plunger die in firm relation to the curl forming grooves 81, thereby to cause complete recurling in multifold form as shown.

When the curl is completed, the plunger die 115 is locked in that position by the latch 125 and latch collar 124, on the rear end of the spindle 113. The spinner head assembly is then quickly returned to its initial position, whereupon the mandrel assembly may be moved out of axial alignment with the spinner head for the purpose of ejecting the spun container body.

While in this position, the cross head 130 is moved toward the arbor by the stud 131 due to means not described. This motion of the cross head transmits an endwise forward motion of the ejector ring 138, by means of the rods 136 to push the spun container body from off the mandrel. During the ejecting motion, a part of the cross head 130 passes over the rear curved extension of the latch 125, thus releasing the plunger die 115 to be returned by the spring 120 to its outer position, after the container is at least partly ejected from the mandrel.

After the ejector device is returned to its rearward position, the mandrel assembly is moved to a position to receive a new container shell, as previously described, whereupon the process may be repeated.

As changes of construction could be made within the scope of the invention, it is intended that all matter contained in the foregoing description or shown in the accompanying drawings shall be interpreted as illustrative and not in a limiting sense.

Having thus described the invention, what is claimed as new and desired to secure by Letters Patent is:

1. In mechanism for incurling the wall edges of conical paper containers, in combination with a mandrel for holding a container, a spinner head

aligned with said mandrel, means to rotate said head, positive means to advance and retract said head, a series of spinner elements movably mounted in said head to contact the container mouth wall edge, and lever means to move said elements in exact proportion to the inclination of the taper of the container as said head is advanced.

2. In an expandable spinner mechanism for the wall edges of conical paper containers, a fixed mandrel on which a container shell is held, a spinner head in register with said mandrel and having means for rotation, means to advance said head, a series of non-rotative spinner elements movable in said head to contact the open end of a container, and means to move said elements outwardly in direct conformity with the constantly increasing taper of the conical container as said head is advanced.

3. An expandable spinner mechanism comprising a frame, a slide mounted thereon, a sleeve journaled in said slide, means for rotating said sleeve, a spindle slidable in said sleeve and rotatable therewith, a spinner head on said spindle, spinner elements pivoted in said head, a spider on said sleeve, and a single means common to said slide and spindle whereby both are moved longitudinally, said means moving the spindle in excess of the movement of said slide, and proportionately thereto.

4. An expandable spinner mechanism comprising a frame, a slide mounted thereon, a sleeve journaled in said slide, means for rotating said sleeve, a spindle slidable in said sleeve and rotatable therewith, a spider on said sleeve, a spinner head on said spindle, spinner elements pivoted in said head, links connecting said spider and spinner elements, a cam actuated lever pivoted on said frame, said lever extending into the axial plane of said spindle, a rigid connection between the end of said lever and spindle, said connection including an anti-friction bearing in which said spindle rotates and an adjustable connection between said slide and lever at a point nearer its fulcrum.

5. An expandable spinner mechanism comprising a frame, a slide mounted thereon, a sleeve journaled in said slide, a spindle slidable in said sleeve and rotatable therewith, a spinner head on said spindle, a plurality of frictional contact spinners pivoted in said head, means to move said spinners outwardly in direct ratio to the advancement of said head, means for rotating said sleeve, means to adjust the relative positional movement of said slide and spindle, a cam actuated lever pivoted on said frame, said lever extending into the axial plane of said spindle, a rigid connection between the end of said lever and spindle, said connection including an anti-friction bearing in which said spindle rotates, and a length adjustable connection between said lever at a point nearer its fulcrum and said slide.

6. In spinner mechanism for taper container wall edges in combination, a slidable head, a sleeve revolute therein and a drive means therefor, a spindle slidable in said sleeve, a cam actuated lever pivoted at one end and connected at different points in its length to said head and spindle respectively, a series of radial former elements movably carried by said spindle, and connections between said elements and sleeve whereby the elements are moved conformably with the motion of said lever into constantly changing distances relative to the axis of said spindle.

7. In a spinner mechanism for taper container wall edges in combination, a mandrel to retain a container, a slidable die in said mandrel to support the container mouth while being spun, means to retain said die when retracted, a cross-head controlling the movement of said die, a ring connected to said cross-head to eject a container from said mandrel, a curling device aligned with said mandrel, said device slidable linearly, means to rotate said device, a plurality of movable spinner elements pivoted in said device, and means for constantly varying the operative radius of said elements in conformity with the taper of the container.

8. In mechanism for incurling the wall edge of tapered paper containers, a mandrel to receive a container, a die slidably axially in said mandrel to project therethrough, a spring to move said die outwardly, detent means to retain said die when retracted, a cross head, means on said cross

head to release said detent, a container ejector ring slidable on said mandrel by said cross head, a series of rotative spinners axially aligned with said mandrel, means to advance and retract said spinners, and means to vary the operative radius of said spinners when advancing in direct ratio to the taper of the container.

9. In a mechanism for incurling the wall edge of tapered paper containers, a mandrel to receive a container, supports for said mandrel, a cross head carried by said supports, a container ejector ring movable on said mandrel by said cross head, a slidably and rotatable head mounted in registration with said mandrel, expandable spinner elements pivoted in said head, and means to expand said elements as said head advances to an extent equal with the taper of the container.

LYDIA B. KOCH.
IRVING F. MANDELL.
